UNITED STATES PATENT OFFICE.

BENJAMIN F. SEYMOUR, OF DENVER, COLORADO, ASSIGNOR TO THE INTERNATIONAL ARMY & NAVY EQUIPMENT COMPANY, OF DENVER, COLORADO.

EXTENSIBLE MAST.

1,250,108.

Specification of Letters Patent. Patented Dec. 11, 1917.

Application filed February 2, 1916. Serial No. 75,772.

To all whom it may concern:

Be it known that I, BENJAMIN F. SEYMOUR, a citizen of the United States, residing at Denver, in the county of Denver and 5 State of Colorado, have invented certain new and useful Improvements in Extensible Masts, of which the following is a specification.

My invention relates to certain new and useful improvements in mechanism for elevating an object from a normal lowered position to a 10 position of greater altitude and wherein certain elevating sections of the mechanism are normally telescoped with each other and 15 with a main or master section and another or central section is nested within the area bounded by the groups of telescoped sections, the nested section being initially elevated relatively to the other and telescoped sections and 20 said telescoped sections being successively elevated relatively to each other and relatively to the main or master section, and said central section adapted as a support and carrier for an accessory, which may 25 be useful in warfare or for other purposes.

More specifically, my invention has reference to an improved extensible mast for use in warfare or other purposes and wherein certain sections of the mast are telescopically 30 or likewise collapsible one within the other and relatively to a stationary normally upright base or master section, and wherein a central, normally-housed section serves as a support and carrier for an observation 35 platform from which the surrounding country may be inspected; or the platform may represent a turret for the support of a gun, or a supporting agency for a signaling apparatus, wireless or otherwise or primarily, in 40 the present instance, for a searchlight, the arrangement being such that when the sections of the mast are in their normal collapsed or folded position the supporting agency or platform occupies or is contained 45 within the area bounded by the permanently upright master or base section, from which latter section the movable sections of the mast may be successively projected first relatively to each other and then relatively 50 to the base section, to properly carry to the appropriate elevation, the searchlight, gun, signal or munition intended to be used in association with the mast.

In the accompanying drawings forming 55 part of this specification and in which simi-

lar reference characters indicate like parts in the several views;—

Figure 1 is a side elevation of an extensible mast embodying my invention and showing the sections of the mast in their 60 normal collapsed positions.

Fig. 2 is a top plan view.

Fig. 3 is a side elevation on a reduced scale, showing the mast extended.

Fig. 4 is an enlarged vertical longitudinal 65 sectional view on the line *a—a* of Fig. 2, showing the sections extended.

Fig. 5 is an enlarged horizontal section on the line *b—b* of Fig. 1.

Fig. 6 is a cross section on the line *c—c* 70 of Fig. 5.

Fig. 7 is a cross section on the line *d—d* of Fig. 5.

In carrying out my invention I employ a foundation or support of some suitable 75 form upon which the mast in both its collapsed and extended positions may be sustained, and which support may be either stationary or movable. For some purposes, I prefer to make the foundation or support 80 of a portable character and hence I illustrate this support in the form of the platform, 10, of a wheeled vehicle, horseless or otherwise and supplied with such accessories as may be of practical use, or such equipment as will be best suited for the particular 85 field of service for which the particular mast is designed.

Upon the platform the master or base section, 11, of the mast is designed to be normally and rigidly sustained in an upright position, in which respect its mounting is different from the base sections of like structures which, ordinarily, are recumbent when in their normal or inactive condition and 95 which are manually raised from the recumbent to an upright position by special appliances, such as haul ropes and guides, sheaves therefor, and the like.

The upright master or base section may 100 be secured to or on the platform in any desired manner, and the height of its projection above the platform and its construction are such that it may receive and form an enclosure or housing for the other or vertically 105 movable sections by which the mast is extensible and the implement or device with which the central section is supplied, may be elevated to such limits as will make it useful for the purposes before mentioned.

While the construction of the base section may vary within wide limits, I prefer and therefore illustrate as a desirable embodiment of my invention, a section composed of 5 corner uprights, 12, of tubular form and spaced to form substantially the corners of a square or rectangle when viewed from above, and as shown in Fig. 2, and the several uprights being connected to stay-rods, 13, or 10 the like to hold them in rigid position, and in parallelism. Tubular or other cross-rods or bars, 19, also connect the uprights to insure greater stability and permanency to this base section and to form mountings for 15 the cross shafts, 17', hereinafter mentioned.

Within each of the corner uprights, 12, is slidably fitted a vertical shaft, 15, which is provided with a thread or equivalent groove of any suitable or desired arrangement and 20 pitch and whose upper end operatively passes through a nut, 16, which so engages the thread of the shaft that when said shaft is rotated relatively to the nut and the fixed upright, it is also raised or lowered according 25 to the direction in which the rotation occurs.

The specific means for rotating the shafts, 15, is unimportant. It may and preferably does, include a normally loose bevel gear, 16', for each of the shafts, said gears being 30 fixed to or otherwise made a part of the aforesaid nuts, and larger or master spur gears, 18, journaled in housings on two of the uprights, 12, and meshing with the spur gears, 17, on shafts, 17', mounted in tubular cross bars, 19, and provided with beveled pinions, 19', each of said master gears having its shaft, 18', fashioned for the operative engagement of a crank, a, which, in practice, 35 will be within convenient reach of an operator standing on a platform, 20, shown by dotted lines in Fig. 3, and which platform may, in fact, represent the hinged lid or corner of a box or receptacle, 21, on the platform of the vehicle shown.

Within each of the shafts, 15, is adapted to slide or telescope another threaded shaft, 22, of substantially equal length thereto, and whose threads operatively engage a fixed 50 nut, 23, mounted on the upper end of each of the said shafts, 15, one of said nuts being loosely carried at each end of the cross-rods or bars, 24, which extend horizontally from one shaft, 15, to another and thereby tie together the several pairs of shafts, 15, to give increased stability and rigidness to the structure and to preserve the shafts, 15, in parallelism and to facilitate their vertical movements with the minimum of friction.

60 To the upper end of each of the threaded shafts, 22, and it will be understood that the construction and operation of the several like shafts are the same, is fixed a spur-gear, 22', the purpose of which will be hereinafter 65 stated.

Within the area bounded by the aforesaid shafts, 15 and 22, is another slidably mounted conveying structure and the one which, in the present instance, serves as the support and carrier of the instrument, machine, apparatus, etc., for the appropriate use of which the extensible mast is designed. This device is herein shown as a searchlight, but manifestly, I do not limit my invention to use therewith, although hereinafter in this description and as a matter of simplicity, I will refer to said device as a searchlight.

The centrally located searchlight supporting structure also comprises suitable shafts, 25, having lower ends mounted in bearings, e, on the cross-bars, l, said shafts, 25, being also suitably braced and stayed by rods, 26, or otherwise, to maintain them truly vertical and in parallelism, and the upper ends of said shafts, 25, carrying spur-gears, 27, which are in mesh with the spur-gears, 22', on the threaded shafts, 22. The gears are contained in casings, e, at the ends of cross-rods f, as shown and which assist in holding the shafts together.

Between the several vertical shafts, 25, extends a platform, 28, upon which the base portion, 29, of the searchlight is mounted, and which base portion may house the complementary mechanism (not shown), usually associated with similar structures for facilitating the control thereof and varying the position of the reflecting surface and therefore the direction of the light rays, etc.

At the ends of the platform, 28, there are 100 secured or otherwise positioned suitable nuts, 30, through which pass the lower ends of the vertical shafts, 25, (Fig. 1), the arrangement being such that as these shafts are turned, the nuts, 30, are caused to advance upwardly 105 thereon, thereby raising the platform and its superposed searchlight and projecting the latter to a point a substantial distance above the top of the mast-structure. Upon the platform, 28, may be positioned an operator, 110 who from this point of observation is enabled to control the position of the searchlight either directly or through some signaling apparatus to an operator below and give such instructions as will enable the latter to 115 turn the searchlight in any particular direction, so that its rays may illuminate the desired distant object; also to enable the observer to correct defects in adjustment of the usual electric light carbons, with which 120 searchlights are usually supplied.

For the better protection of the gearing from the influence of foreign matter, I prefer to locate them in appropriate housings or casings, and I may employ such other 125 mechanical accessories or details for the strengthening of the structure and to insure its rigidity and for the protection of its parts and the operators thereof, as may be found either necessary or desirable, these 130

being mere mechanical expedients which have no essential bearing upon the broader features of my invention.

In the operation of the device and assuming for present purposes that the extensible mast is mounted upon a wheeled vehicle, this vehicle is driven to the desired place with the sections of the mast collapsed or folded as in the position shown in Fig. 1, and wherein the searchlight supporting features are contained wholly within the area bounded by the inner walls of the rigid upright base section. On arriving at the desired point, operators standing on the platform, 20, will turn the cranks, *a*, through the gears, 18, 17, and 19', and geared cross-shafts will give rotation to the series of threaded shafts, 15, and also to the series of beveled gears, 16', and the nuts, 16, through which the shafts pass and which gears, 16', are loosely mounted, whereby the shafts and gears and nuts turn in unison and no movement in a vertical direction is imparted to said shafts. The rotation of the shafts, and the friction between the same and the interior shafts, 22, will, however, cause the rotation of the inter-meshing gears, 22', and 27, at the top between the shafts, 15, and the shafts, 25, of the light supporting structure, and the result is that rotation is now imparted to the shafts, 25, and as the latter are of smaller diameter than the shafts, 22, and in practice will have threads of greater pitch than those of the shafts, 22, said shafts, 25, will work in the nuts, 30, at the ends of the platform, 28, and cause the platform and supported searchlight to be vertically raised until the nuts or some other suitable portion of the moving structure engages from below the casing of the gear wheels, 27, at the top of the shafts, 25, or some other suitable stop, which operation holds the nuts against further travel and retards the rotation of and substantially locks the shafts, 25, against rotation and at the same time locks the gears, 22'-27, and shafts, 22, against further rotation. This rotates the series of screw shafts, 22, which being of smaller diameter than the screw shafts, 15, and having in practice threads of a sharper pitch than the latter, will turn in the nuts, 23, independently of the shafts, 15, and advance out of the shafts, 15, carrying the central light supporting section with them, and until the ends of the threads are reached, when further rotation is checked. In this condition of the parts, the continued manipulation of the crank handles, *a*, and the conversion of its motion through the gears, 18, 17 and 19', to the loose gears, 16', and attached nuts, will now cause the latter to so engage with the threads of the shafts, 15, that these shafts are moved upwardly carrying with them the elevated shafts, 15 and 22, and the interior searchlight supporting structure,

namely, the shafts, 25, the platform, 28, and searchlight, until the shafts, 15, have reached the upward limit of their movement, or until the mast has been projected to such elevation as may be desired. In its now extended position, the searchlight is elevated above any portion of the mast structure, so as to secure an unobstructed field for the projection of its rays.

The parts may be collapsed or moved into their normal position by a reverse operation as will be readily understood and when so collapsed, the shafts, 25 and their connections which form the supporting framework for the searchlight will lower into and be wholly contained within the area bounded by the inner walls of the normally upright and rigid base section formed by the tubular uprights and cross connections before mentioned.

Having thus described my invention what I claim as new and desire to secure by Letters Patent is:

1. A sectional mast having a movably mounted section adapted to normally lie within the area bounded by the interior dimensions of another section and being open at the top, said movably mounted section having a conveying platform normally positioned near the base of the other section, and means for elevating said platform relatively to its own section to carry the supported load to the upper limits of the latter.

2. A sectional mast having a movably mounted section adapted to normally lie within the area bounded by the interior walls of another section and being open at the top, said movably mounted section having a conveying platform normally positioned near the base of the other section, and means for elevating said platform relatively to its own section and to the companion section, to carry the supported load to the upper limits of its own section.

3. A sectional mast having a base or master section normally and permanently sustained in an upright position, and a plurality of extensible sections, one of said latter sections being telescopically fitted to the main or master section and another of said extensible sections adapted to normally nest within the area bounded by the interior of the first-named extensible section and being open at the top and carrying a movably mounted conveying platform which normally lies in the lower portion of said nested section.

4. A sectional mast having a base or master section normally and permanently sustained in an upright position, and a plurality of extensible sections, one of said latter sections being slidably fitted to the main section and another of said extensible sections adapted to normally nest within the area bounded by the interior of the first-

named extensible section and being open at the top and carrying a movably mounted load support, and means for raising and lowering said support relatively to its own section.

5. A sectional mast having a base or master section normally and permanently sustained in an upright position, and a plurality of extensible sections, one of said latter sections being slidably fitted to the main section and another of said extensible sections adapted to normally nest within the area bounded by the interior of the first-named extensible section and being open at 10 the top and carrying a movably mounted load support which normally lies in the lower portion of said nested section, and means for raising and lowering said support relatively to its own section and to said 15 base section.

6. A sectional mast having a base-section normally and permanently sustained in an upright position and comprising a series of spaced parallel tubular members; a series of 25 extensible sections provided with spaced parallel, vertical screw-shafts, the series of one of said extensible sections telescopically fitting the series of tubular members of said base section, and the series of vertical shafts 30 of the other extensible section being normally parallel with the shafts of the first-named extensible section whereby one extensible section may normally nest within the area bounded by the shafts of the other 35 section, gearing between the upper portions of the extensible sections, and operating means on the base section including rotatable nuts engaging the screw shafts of the first-named extensible section.

40 7. An extensible mast having a base section and a series of extensible sections, one of said extensible sections being slidable vertically in line with the base section and another extensible section being vertically slid- 45 able within the base section and parallel to the first-named extensible section so that it may be lowered into and be normally nested within the area bounded by the inner walls of the main section, said nesting section having 50 vertical parallel screw shafts, and a

load support normally lying in the base of the mast and having nut-members receiving the screw shafts of the nesting section whereby upon the rotation of said last-named shafts the load support is elevated 55 relatively to the base section to carry the support to substantially the top of the latter.

8. An extensible mast having a base section and a series of extensible sections, one of said extensible sections being slidable vertically in line with the base section and another extensible section being vertically slid- 60 able in a plane which is inferior to the plane of the base section and parallel to the first-named extensible section so that it may be 65 lowered into and be normally nested within the area bounded by the inner walls of the main section, said nesting section having vertical, parallel screw shafts, and a load support normally lying in the base of the 70 mast and having nut-members receiving the screw shafts of the nesting section whereby upon the rotation of said last-named shafts the load support is elevated relatively to the base section to carry the support to substantially 75 the top of the latter, and connections between the upper portions of the several sections adapted to elevate the sections in unison and while the load support is in its elevated situation.

9. A sectional mast provided with a plurality of opposed upright sections and other sections co-acting therewith and vertically movable relatively thereto, an interior conveyer section centrally disposed within the 85 area bounded by the other sections and being open at the top, and means for raising and lowering the conveyer section in relation to the said upright sections.

10. A sectional mast provided with an in- 90 terior centrally-disposed open top section, a load-support and means for moving the same toward and from the open top of said central section, and a contrivance on the support and exposable through the open top of 95 the section when the load support is in its elevated position.

In testimony whereof I affix my signature.

BENJAMIN F. SEYMOUR.
